Design No. 3,435, dated March 30, 1869.

DESIGN FOR A TRADE-MARK.

The Schedule referred to in these Letters Patent and making part of the same.

To all whom it may concern:

Be it known that we, JOHN A. HAMLIN and LYSANDER B. HAMLIN, of the city of Elgin, in the county of Kane, and State of Illinois, have originated or designed a new Design for a Trade-Mark, of which the following is a full, clear, and exact description, reference being had to the accompanying samples, which are printed, instead of being drawn.

We intend to use said trade-mark more particularly as a label, to be used upon bottles and packages of bottles, containing a medicine, which we manufacture and call "Hamlin's Wizard-Oil."

We shall print on the same label the names of the diseases which the wizard-oil cures; also directions, and

various other matter, that may be changed, from time to time; but

Our invention consists in the miniature hereto attached, in connection with the words "Hamlin's Wizard-Oil;" and

What we claim, and desire to secure by Letters Patent, is—

The design for a trade-mark, herein set forth.

JOHN A. HAMLIN.
